CLAIM

The ornamental design for a front panel for a room air conditioner, as shown and described.

DESCRIPTION

FIG. 1 is a perspective view of a front panel for a room air conditioner showing our new design.

FIG. 2 is an enlarged front elevational view of a front panel for a room air conditioner showing our new design.

FIG. 3 is an enlarged top plan view of a front panel for a room air conditioner showing our new design; and,

FIG. 4 is an enlarged left side elevational view of a front panel for a room air conditioner showing our new design, the right side elevational view being a mirror image.

The bottom and rear of the front panel for a room air conditioner form no part of the claimed design.
